[57] CLAIM

The ornamental design for a television set, as shown and described.

DESCRIPTION

FIG. 1 is a left side elevational view of a television set showing my new design, the right side being a mirror image;

FIG. 2 is a front elevational view thereof;

FIG. 3 is a rear elevational view thereof; and

FIG. 4 is a top plan view thereof.

The bottom of the television set is unornamented.

FIG. 1

FIG. 2

FIG. 3

FIG. 4
